UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-PRESSING MACHINE.

Application filed December 14, 1927. Serial No. 240,041.

This invention relates to machines for applying pressure to the bottoms of shoes, and more particularly to machines of that class in which a shoe support and a pressing or leveling tool, such as a roll, are relatively movable to cause the tool to operate progressively along the bottom of a shoe. The invention is herein illustrated in its application to a machine organization of the same general type as that disclosed in Letters Patent No. 1,667,761, granted on May 1, 1928, upon an application of E. E. Winkley and H. A. Davenport, and in various Letters Patent therein referred to, although it is to be understood that in its more general aspects the invention is not thus limited in its applicability.

Machines of the above-mentioned type comprise in their organization a spring for pressing the leveling tool yieldingly on the shoe and automatic means for controlling the pressure applied to the shoe through the spring in the course of the leveling operation. In such control an object is to provide for adequate pressure on both the forepart and the shank portions of the shoe bottom, and also under some conditions to relieve the pressure on one or more portions of the shoe bottom. In the use of the machine, for example, on shoes that have high-arched shanks, it is desirable to relieve the pressure in the vicinity of the ball-line, so that the tool will not fall too abruptly from the ball into the shank and will not meet too much resistance in returning from the shank to the forepart. Moreover, in operating on shoes of a style characterized by a pronounced line or ridge across the sole at the ball of the shoe, it is desirable thus to relieve the pressure in order to prevent the tool from obliterating such a line or ridge. It is likewise desirable to relieve the pressure at the beginning and at the end of the leveling operation in order to prevent damage to the toe end of the sole, as fully explained in the above-mentioned Letters Patent No. 1,667,761.

An object of the present invention is to provide simple and conveniently operable means for controlling the pressure of a leveling tool on a shoe in such manner as to relieve the pressure effectively where desired and yet to apply the amount of pressure required for the best results in operating on other portions of the shoe. For the purposes

in view the construction shown comprises means whereby the tool support or carrier may be released from the force of the pressure spring to effect the relief of pressure on the shoe, while yet maintaining the spring under a predetermined degree of stress to be rendered immediately effective on the shoe as soon as the pressure is again applied. Preferably, as shown, the machine also includes in its organization means such as disclosed in the above-mentioned Letters Patent for supporting the weight of the tool and its carrier, and it may be also for lifting these parts, when the relief of the pressure takes place, the arrangement accordingly being such that the tool may be lifted, for example in passing from the shank up over the ball-line, without opposition from the pressure spring, notwithstanding the fact that the spring is still held under stress. The invention thus provides novel means whereby a complete release of the pressure on the shoe may be effected where required, and yet whereby the shoe may be immediately subjected again to adequate pressure as soon as the pressure is again applied. The invention still further provides a novel organization of means for varying the minimum stress of the pressure spring to determine the degree of pressure applied to the shoe, and also for effecting such an adjustment as to prevent the release of the tool carrier from the force of the spring in the manner above set forth in operating on shoes of such a style as not to require a complete release of the pressure at the ball-line.

In accordance with a further feature of the invention there is provided a novel organization of means for determining the time or times in the cycle of operations of the machine when the relief of the pressure of the tool on the shoe takes place, whether or not there be a complete release of the pressure as hereinabove described. In different styles of shoes there is frequently a variation in the relation between the length of the forepart and the length of the shank in shoes of the same size. In view of this and other conditions, the machine herein shown includes in its organization means for suitably varying the time in the cycle of operations when the relief of the pressure takes place in each traverse of the leveling tool over the ball portion of the shoe, so that the relief of the pressure

will occur at precisely the time best suited to the particular style of shoe. As herein illustrated, the relief of the pressure each time at the ball-line is controlled by means which is 5 adjustable to vary the time when the pressure is relieved and which is associated with a series of cams operating at fixed times in the cycle to apply the pressure substantially as heretofore. It will accordingly be evident 10 that by the construction herein shown there may be effected a relative variation between the time of application and the time of relief of the pressure so that the duration of the pressure relief will likewise be varied, as is 15 desirable in accommodating the machine to different conditions that may be met with in operating upon shoes of different shapes.

The above and other features of the invention, including various novel details of 20 construction and combinations of parts, will now be more particularly described by reference to the accompanying drawings and pointed out in the claims.

In the drawings,

25 Fig. 1 is a view in side elevation, with parts in section, showing a machine of the type disclosed in the prior Letters Patent hereinbefore mentioned, with the present invention embodied therein;

30 Fig. 2 is a perspective view from the right-hand side of Fig. 1, showing a portion of the mechanism for variably timing the relief of the pressure of the leveling tool on the shoe;

35 Fig. 3 shows more in detail the cam mechanism illustrated in Fig. 2, as viewed from the left-hand side of that figure;

Fig. 4 is a view in left-hand end elevation of the mechanism shown in Fig. 3;

40 Fig. 5 is a detail view in side elevation, showing a portion of the mechanism for variably timing the pressure relief, with the parts in different positions from those illustrated in Fig. 1; and

45 Fig. 6 is a detail view, partly in side elevation and partly in section, showing a portion of the mechanism through which the pressure is yieldingly applied to the shoe.

Leveling machines of the type illustrated are twin machines comprising in their organization two sets of operating instrumentalities for operating respectively on different shoes in different locations in the machine. For the purpose of an understanding of the present invention reference will 50 be made to only one of these sets of instrumentalities, since it will be understood that, except as will appear hereinafter, mechanism such as illustrated as an embodiment of the invention will be duplicated in the opposite halves of the machine, and it is further to be understood that in its more general aspects the invention is not limited to machines of the twin type.

60 The shoe *a* to which leveling or shaping pressure is to be applied is mounted upon a

shoe support or jack comprising a heel post 10 and a toe post 12 which are relatively adjustable as heretofore for shoes of different sizes, the jack as a whole being movable about an axis at 14 to carry the shoe forwardly and rearwardly beneath a leveling roll 16. The roll 16 is mounted in a holder 18 which is supported on a roll carrier 20 pivotally mounted at 22 on the frame of the machine for swinging movements in a vertical plane to press the roll 16 upon the shoe and to relieve the pressure at different respective times in the operation of the machine. To cause the roll to operate along the bottom of the shoe the jack is swung about 70 its axis 14 by power-operated mechanism comprising a path cam 24 on a cam shaft 26 and connections which it is unnecessary to describe in detail for an understanding of the present invention, such mechanism being 75 fully disclosed in prior Letters Patent including those hereinbefore referred to. Generally speaking, the cycle of operations comprises first a movement of the jack to cause the roll to traverse the shoe from the toe 80 end to the heel-seat, then a plurality of backward and forward movements while the roll is operating in the shank, thereafter a movement to cause the roll to return to the toe end of the shoe along one side and then to 85 traverse the sole from the toe to the heel-seat along the opposite side, followed by a plurality of backward and forward movements to cause the roll to operate in the shank at 90 that side, and finally a movement to cause the roll to return to the toe and to leave the shoe. In the course of these operations the roll is tipped in various ways by movement 95 of its holder 18 relatively to the carrier 20 by mechanism which is also disclosed in prior Letters Patent and need not be described in detail for an understanding of this invention.

100 In the course of the cycle of operations the pressure of the roll 16 on the shoe is controlled through a spring 28 by means including a cam wheel 30 fast on the cam shaft 26. The spring 28 is arranged to apply its pressure to a lever 32 which is pivoted at 34 on the frame of the machine and is connected by a link 36 to the roll carrier 20. For controlling the spring 28 there is provided a lever arm 38 fast on a rock-shaft 40 which has also fast thereon an arm 42 connected by a link 44 to a lever 46 pivoted at 48 on the frame of the machine and provided with a roll 50 in engagement with the periphery of the cam wheel 30. The lever arm 38 is arranged to bear on ears 52 formed on opposite sides of a sleeve member 54 which is slidingly movable in a holder 56 on the frame of the machine and engages the upper end of the spring 28. For purposes of the present invention a rod 58 extends downwardly through the sleeve 54 in sliding engagement therewith 105 110 115 120 125 130

and through the spring 28, the lower end of the rod having screw threads thereon in engagement with co-operating threads in a member 60 which is seated on the lever 32 and serves as an abutment for the lower end of the spring. Fast on the upper end of the rod 58 is a hand-wheel 62 which abuts against one end of the sleeve member 54 and by which the rod may be turned to vary the 10 distance between the members 54 and 60 and thus to vary the degree of compression of the spring 28.

It will thus be seen that the members 54 and 60 and the threaded rod 58 with its hand-wheel 62 constitute a holder for the spring 28, and that when the parts of the holder are suitably adjusted and the lever arm 38 is so far retracted as to release the ears 52 of the member 54, as illustrated in Fig. 1, the spring 20 and its holder are free to move vertically as a unit to release the lever 32 and the roll carrier 20 from the force of the spring, notwithstanding the fact that the spring is still held under compression. Accordingly, at each 25 time in the cycle when relief of the pressure on the shoe takes place, for example in traversing the ball-line of the shoe, the spring 28 may be rendered inoperative as far as its action on the roll carrier is concerned, while 30 still being held under a predetermined degree of compression so that when the pressure is again applied to the shoe by the action of the cam wheel 30 the shoe will immediately be subjected to a pressure corresponding to 35 the stress of the spring. In this manner the pressure may be effectively relieved at the portion of the shoe desired, and yet the shoe may be subjected to the amount of pressure required for the best results immediately 40 when the pressure is again applied. It will be understood that each of the twin sets of operating instrumentalities will include a separate spring 28 and a holder therefor, as described, together with a separate operating 45 arm 38 fast on a common rock-shaft 40 operated by the single cam wheel 30 through the parts 42, 44 and 46.

Preferably, although not necessarily, there will be combined with the pressure relief 50 mechanism above described a device of the same general character as that shown and described in Letters Patent No. 1,667,761 hereinbefore mentioned for supporting the weight of the roll carrier 20 and the 55 roll 16 with its holder 18, and it may be for also lifting these parts at each time when the roll carrier is released from the force of the spring 28. This device comprises a spring-controlled plunger 64 which 60 is mounted for vertical movement in a holder 66 on the frame of the machine and is arranged to engage the lower face of the front end of the roll carrier 20. It will be understood that the force with which the plunger 65 64 engages the carrier 20 may be adjusted by

mechanism not shown in detail but disclosed in the Letters Patent referred to, so that the plunger may either act simply to sustain the weight of the carrier and the parts supported thereon or actually to lift these parts at the 70 time of the pressure relief, for example as the roll passes from the shank up over the ball-line of the shoe.

As hereinbefore explained, the minimum stress of the spring 28 may be adjusted by 75 turning the handle-wheel 62 to vary the pressure applied to the shoe, and there is further provided means for effecting a compensating adjustment of the lever arm 38 to position it in the desired relation to the ears 52 on the member 54, in order to avoid, for example, an undesirable amount of lost motion between the arm and the ears 52. For this purpose the link 44 comprises a rod having a hand-wheel 68 thereon and provided at its opposite ends with right- and left-hand threads respectively for engagement with corresponding threads in members 70 and 72 which are connected respectively to the arm 42 and to the lever 46. By turning the hand-wheel 68, 80 therefore, the effective length of the link 44 may be varied to vary the relation of the arm 38 to the ears 52 and correspondingly to vary the limit of operative movement of the arm 38 without affecting the extent or amplitude of 85 its movement. Any desired relation between the arm 38 and the ears 52 at the time of the pressure relief may thus be provided for. If it is not desired that the roll 16 be actually 90 lifted out of contact with the shoe, the arm 38 may be so adjusted as still to engage the ears 52 even though the spring 28 is expanded to the limit determined by its holder, so that the arm 38 will co-operate with the plunger 64 in maintaining the roll barely in contact 95 with the shoe without any substantial pressure thereon. Furthermore, it will be evident that by suitable adjustment of the link 44 in co-operation with the adjustment of the hand-wheel 62 the parts may be so positioned 100 that the roll carrier 20 will not be entirely released from the force of the spring 28 at 105 the time when the relief of the pressure on the shoe occurs, as may be desirable in operating upon some styles of shoes. It will likewise 110 be evident that adjustment of the link 44 will serve in itself to vary more or less the pressure applied to the shoe.

The cam wheel 30 is so formed as to control 115 the pressure of the roll on the shoe in the same general relation to the cycle of relative movements of the roll and the jack as heretofore, except as modified in the manner hereinafter described for purposes of the present 120 invention. That is to say, the cam wheel is provided with a cam 74 for applying the pressure first at the forepart of the shoe, with a depression 76 corresponding to the first relief of the pressure at the ball-line, a cam 78 125 for applying pressure while operating at one 130

side of the shank, a depression 80 corresponding to the relief of the pressure in returning over the ball-line, a cam 82 for applying the pressure in operating forwardly over the 5 forepart at one side and in returning along the forepart at the other side, a depression 84 corresponding to the first relief of the pressure at the ball-line on that side, a cam 86 for applying the pressure in operating in 10 the shank at that side, a depression 88 corresponding to relief of the pressure in returning over the ball-line, a cam 90 for applying pressure again at the forepart, and a final depression 92 corresponding to relief of the 15 pressure as the roll leaves the shoe at the toe and also at the beginning of the cycle of operations at the toe of the next shoe.

In accordance with a further feature of the present invention, there is provided novel 20 means for determining the time or times in the cycle of operations when the relief of the pressure takes place. It is especially desirable to determine precisely the time of the pressure relief at the ball of the shoe in accordance with the style of shoe, in view of the 25 varying shapes of different styles of shoes including variations in the length of the forepart as compared with that of the shank such as frequently occur in different shoes of the 30 same size. For the purposes in view the machine herein shown includes in its organization means operative independently of the cam wheel 30 for determining the time of the pressure relief at each part of the cycle where it occurs, with provision for adjustably varying 35 the time of the pressure relief at the ball of the shoe. By reference to Fig. 1 it will be seen that there is mounted adjacent to one side of the cam wheel 30 a cam plate 94 which is formed 40 on one end of an arm 96, the latter being pivotally supported at one end on an arm 98 which is pivoted at 100 on the frame of the machine, and pivotally supported at its other end on a member 102 which is mounted on a rock-shaft 45 104 on the frame. It will thus be seen that by swinging movement of the supporting members 98 and 102 the cam plate 94 may be moved to the right and left (Fig. 1). The roll 50 which is engaged by the cam wheel 50 30 is long enough to be engaged also by the cam plate 94, so that the cam plate may be moved into position under the roll to support it in the position to which it is moved by any one of the cams on the cam wheel. A spring 55 plunger 106 (Fig. 1) is arranged to act on the arm 98 to move the cam plate 94 thus into position under the roll, as illustrated for example in Fig. 5, each time that the roll is lifted by the cam wheel 30. When the cam plate 60 is thus positioned under the roll 50 it maintains the pressure of the leveling roll 16 on the shoe independently of the cam wheel 30 after any one of the cams on the cam wheel 65 has passed beyond the roll, and in the construction shown the depressions between the

cams of the cam wheel are of such length that each cam will have passed beyond the roll at least by the time when it is necessary to relieve the pressure in operating on any size or style of shoe, the relief of the pressure occurring at the time when the cam plate 94 is moved toward the left (Fig. 1) to release the roll. For thus controlling the cam plate 94 there is provided a series of power-driven cams 108, 110, 112, 114 and 116 (Figs. 2, 3 70 and 4) corresponding to the depressions 76, 80, 84, 88 and 92 in the cam wheel 30. These cams are mounted to turn as a unit about a shaft 118 and are driven from the cam shaft 26 by a chain 120 in engagement with a sprocket wheel 122 connected to the cams. The sprocket wheel 122 is fast on the hub of 75 a disk 124 which is keyed to a hub 126 rotatably mounted on the shaft 118 between collars 128 and 130 secured to the shaft. The disk 124 has mounted to turn thereon a lug 132 in which is swivelled a screw 134 in threaded engagement with a lug 136 mounted to turn on a disk 138 rotatable about the hub 126 and on which the cam 108 is formed. At 80 the other end of the series of cams there is fast on the hub 126 a disk 140 similarly provided with a lug 142 and a screw 144 in engagement with a lug 146 on a disk 148 rotatable about the hub 126 and on which the cam 114 is formed. In the center there is fast on the hub 126 a disk 150 on which the cam 116 is formed, and mounted to turn about the hub at one side of this disk is a disk 152 which carries the cam 110, and at the opposite side 85 thereof a disk 154 which carries the cam 112. The disks 152 and 154 have elongated slots 156 and 158 therein through which extend from the central disk 150 bolts 160 and 162 provided with supports for screws 164 and 166 connected respectively to lugs carried by the disks 152 and 154. It will thus be seen that each of the four cams 108, 110, 112 and 114 is independently adjustable about the axis 90 of its turning movement, these cams being the ones which control the relief of pressure on the shoe at the ball-line at different times in the cycle of operations. The central cam 116 controls the relief of pressure at the end of the toe, and is not adjustable since the toe ends of all shoes occupy the same initial position in relation to the roll 16. The different cams are arranged to act in succession upon a roll 168 which is supported between a pair of 95 connected arms 170 mounted to turn on the rock-shaft 104 and arranged to engage a roll 172 on the member 102 for operating this member to move the cam plate 94 to the left 100 (Fig. 1).

From the foregoing description it will be seen that there is provided means for controlling independently of the cam wheel 30 the relief of the pressure of the leveling roll on the shoe each time that it occurs, and means for adjustably varying the time of the 105 110 115 120 125 130 135

relief of pressure at each traverse of the roll over the ball of the shoe. The pressure is applied each time by the appropriate cam on the cam wheel 30, and in the construction shown the time of such application of pressure is therefore invariable, since it is found to be unnecessary to provide for adjustment in this respect if the cam wheel 30 is formed, as it is in the machine shown, to provide ample leeway in respect to the time of application of the pressure for shoes of different styles so that the pressure will not be applied too soon in operating on any style of shoe. It will be evident that since the mechanism disclosed thus provides for variation in the time of the relief of the pressure relatively to the time of the application of pressure, it affords provision for a variation in the duration of the pressure relief at the ball portion of the shoe, which is desirable in accommodating the machine to produce the best results in operating on shoes of different styles.

Fig. 1 shows the parts as positioned prior to the starting of the machine, the roll 50 resting in the depression 92 of the cam wheel 30 and the cam plate 94 being held in a retracted position by means of the cam 116. When the machine is started the cam 74 first becomes effective to raise the roll 50 and thereby press the leveling roll upon the shoe after the jack has moved far enough to carry the end of the toe under the roll. At the same time the cam 116 moves out from under the roll 168 and thereby releases the cam plate 94 to the action of the plunger 106, and as soon as the cam roll 50 has been raised to the top of the cam 74 the cam plate 94 is moved by the plunger into position to support the roll independently of the cam 74 after this cam has passed from under the roll, as illustrated in Fig. 5. At the time in the cycle determined by the adjustment of the cam 108 this cam becomes effective to move the cam plate 94 out from under the roll and thus permit the roll to drop into the depression 76 of the cam wheel 30 to relieve the pressure on the shoe as the roll first traverses the ball-line, the cam 78 thereafter becoming effective to apply the pressure in the shank. In a similar manner successive relief of pressure and application of pressure are effected at the other successive times in the cycle when the roll traverses the ball-line, and at the end of the cycle relief of pressure as the roll passes off the toe end of the shoe is controlled by the cam 116. It will be understood that each time when the relief of the pressure takes place the shoe may be either entirely released from the pressure or may be subjected only to a lesser degree of pressure, depending upon the adjustment of the pressure spring 28 and the controlling mechanism associated therewith, as hereinbefore explained.

While the invention is illustrated with particular reference to the leveling of the out-

soles of shoes, it will be understood that machines of the type herein shown are not restricted to that particular use, but are applicable, for example, to the pressing of the inseams of welt shoes before the outsoles are applied, and accordingly the term "leveling" is herein employed, not by way of limitation, but in an inclusive sense to comprehend the various uses for which machines of this type are adapted.

Having described the invention, what I claim as new and desire to secure by Letters Patent of the United States is:—

1. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, and means including a spring for controlling said carrier to apply and relieve the pressure, said means being constructed to release the carrier from the force of the spring at a predetermined time in the operation of the machine on the shoe while yet maintaining the spring under a predetermined degree of stress.

2. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, and mechanism including a spring for operating said carrier to press the tool on the shoe and for controlling the pressure in the course of the leveling operation, said mechanism being constructed to release the carrier from the force of the spring at that time in the cycle of operations of the machine when the tool is traversing the ball-line of the shoe while yet maintaining the spring under a predetermined stress.

3. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, and cam-controlled mechanism including a spring for controlling said carrier to apply the pressure yieldingly to the shoe and to relieve the pressure at that time in the cycle of operations of the machine when the tool is traversing the ball-line of the shoe, said mechanism including also a device for controlling the spring so constructed as to release the carrier completely from the force of the spring while yet maintaining the spring under stress when the pressure is thus relieved.

4. In a machine of the class described, a shoe support and a leveling tool relatively movable to cause the tool to operate along the bottom of a shoe, a carrier supporting said

tool and movable heightwise of the shoe to press the tool upon the shoe, and cam-controlled mechanism including a spring for operating said carrier to press the tool on the shoe and for controlling the pressure in the course of the leveling operation, said mechanism being constructed to release the carrier from the force of the spring at a plurality of times in the cycle of operations of the machine while yet maintaining the spring under stress.

5. In a machine of the class described, a shoe support and a leveling tool relatively movable to cause the tool to operate along the bottom of a shoe, a carrier supporting said tool and movable heightwise of the shoe to press the tool upon the shoe, a spring through which to operate said carrier to press the tool on the shoe, a device for controlling 10 said spring as a whole to maintain it under stress at all times in the operation of the machine, and mechanism arranged to act through said controlling device to apply the force of the spring to said carrier in operating on the shoe and at a predetermined time in the cycle of operations of the machine to release the carrier from the force of the spring while the spring remains under stress.

6. In a machine of the class described, a shoe support and a leveling tool relatively movable to cause the tool to operate along the bottom of a shoe, a carrier supporting said tool and movable heightwise of the shoe to press the tool upon the shoe, a spring through which to operate said carrier to press the tool on the shoe, a device for controlling said spring as a whole to limit it to a predetermined minimum stress, and mechanism arranged to act through said controlling device to apply to the tool carrier the force of the spring thus determined and to increase said force in operating on the shoe and at a predetermined time in the cycle of operations of the machine to release said carrier from the force of the spring while the spring remains under stress.

7. In a machine of the class described, a shoe support and a leveling tool relatively movable to cause the tool to operate along the bottom of a shoe, a carrier supporting said tool and movable heightwise of the shoe to press the tool upon the shoe, a spring through which to operate said carrier to press the tool on the shoe, and automatic mechanism for controlling said spring to relieve the pressure of the tool on the shoe at a predetermined time in the operation of the machine and thereafter again to apply the pressure, said mechanism being constructed to release the carrier from the force of the spring to effect such relief of the pressure while yet maintaining the spring under a predetermined degree of stress to be rendered immediately effective on the shoe when the pressure is again applied.

8. In a machine of the class described, a shoe support and a leveling tool relatively movable to cause the tool to operate along the bottom of a shoe, said tool being movable heightwise of the shoe to apply pressure to the shoe, a member for operating said tool to press it on the shoe, another member movable to operate said first member to apply the pressure and thereafter retractable to release the pressure, a spring for applying the force of said movable member to the first member, and a device for controlling said spring constructed and arranged to release said first member from the force of the spring in response to the retracting movement of said movable member while yet maintaining the spring under a predetermined degree of stress.

9. In a machine of the class described, a shoe support and a leveling tool relatively movable to cause the tool to operate along the bottom of a shoe, a carrier supporting said tool and movable heightwise of the shoe to press the tool upon the shoe, a spring through which to operate said carrier to press the tool on the shoe, a holder for said spring constructed to engage the spring at both ends to hold it under compression and prevent it from completely expanding in the operation of the machine, and a member movable in the operation of the machine to apply the force of the spring to the carrier through said holder and also movable to release the holder, the spring and its holder being mounted for movement as a unit when thus released to free the tool carrier from the force of the spring while the spring is still held under compression.

10. In a machine of the class described, a shoe support and a leveling tool relatively movable to cause the tool to operate along the bottom of a shoe, and power-operated mechanism for controlling the pressure of said tool on the shoe in the course of the operation of the machine, said mechanism comprising members relatively movable toward and from each other to increase and lessen the pressure respectively, a spring interposed between said members, and a holder for said spring constructed to maintain it under compression irrespective of the extent of the relative separating movement of said members, said spring and its holder being so mounted as to release the tool from the force of the spring in response to the relative separating movement of said members while maintaining the spring under compression.

11. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, means including a spring for controlling said carrier to apply and relieve the

pressure, said means being constructed to release the carrier from the force of the spring at a predetermined time in the operation of the machine while yet maintaining the spring under a predetermined degree of stress, and means for adjustably varying the stress of the spring.

12. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a member movable to operate said carrier to apply the pressure and retractable to relieve the pressure, a spring for applying the force of said member to the carrier, and a holder for said spring constructed and arranged to release the carrier from the force of the spring in response to the retracting movement of said member while maintaining the spring under a predetermined degree of minimum compression, said holder being adjustable to vary the degree of minimum compression of the spring.

13. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring through which to operate said carrier to apply the pressure to the shoe, a holder for said spring comprising members arranged to engage the spring at its opposite ends to prevent it from completely expanding in the operation of the machine, and a lever arranged to operate on one of the members of said holder to apply the pressure of the spring to the carrier and retractable to release the holder at a predetermined time in the operation of the machine on the shoe, said spring and its holder being mounted for movement as a unit when the holder is thus released by said lever to release the carrier from the force of the spring and the members of the holder being relatively adjustable to vary the compression under which the spring is held when the holder is thus released.

14. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring through which to operate said carrier to apply the pressure to the shoe, a holder for said spring comprising members for engaging the spring at its opposite ends to prevent it from completely expanding in the operation of the machine, a lever arranged to operate on one of said members to apply the pressure of the spring to the carrier and movable in a direction away

from said member to release the holder at a predetermined time in the operation of the machine on the shoe, said spring and its holder being so mounted as to release the carrier from the force of the spring when the holder is thus released by the lever, means for relatively adjusting said members to vary the compression of the spring and to vary the distance between the lever and the member on which it operates, and means for effecting a compensating adjustment of said lever.

15. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring through which to operate said carrier to apply the pressure to the shoe, a holder for said spring comprising members for engaging the spring at its opposite ends to prevent it from completely expanding in the operation of the machine, a lever arranged to operate on one of said members to apply the pressure of the spring to the carrier and movable in a direction away from said member to release the holder at a predetermined time in the operation of the machine on the shoe, said spring and its holder being so mounted as to release the carrier from the force of the spring when the holder is thus released by the lever, means for relatively adjusting said members to vary the compression of the spring and to vary the distance between the lever and the member on which it operates, a link for operating said lever, and means for varying the length of said link to adjust the lever relatively to the holder.

16. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring through which to operate said carrier to apply the pressure to the shoe, a member arranged to operate on said spring, and means for imparting to said member an operative movement of predetermined extent, said member being adjustable to vary the limit of its operative movement without affecting the extent of its movement.

17. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring through which to operate said carrier to apply the pressure to the shoe, a lever arranged to operate on said spring, means including a link for imparting to said lever an operative movement of predetermined extent, and means for varying

the length of said link to vary the limit of the operative movement of the lever without varying the extent of its movement.

18. In a machine of the class described, a shoe support and leveling tool relatively movable to cause the tool to operate along the bottom of a shoe, a carrier supporting said tool and movable heightwise of the shoe to press the tool upon the shoe and to relieve the pressure, and means including a spring for controlling said carrier to apply and relieve the pressure, said means being constructed to release the carrier from the force of the spring at a predetermined time in the operation of the machine on a shoe while yet maintaining the spring under a predetermined degree of stress and being also adjustable to prevent such release in operating on a shoe.

19. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, and automatically operative mechanism including a spring for operating said carrier to press the tool on the shoe and for controlling the pressure in the course of the leveling operation, said mechanism being constructed to release the carrier from the force of the spring at that time in the cycle of operations of the machine when the tool is traversing the ball-line of the shoe while yet maintaining the spring under a predetermined stress and being also adjustable to prevent such release in operating on a shoe.

20. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, an operating member movable to operate said carrier to apply the pressure and also movable at a predetermined time in the operation of the machine on the shoe to relieve the pressure, a spring for applying the force of said operating member to the carrier, and a holder for said spring constructed and arranged to release the carrier from the force of the spring in response to the pressure-relieving movement of the operating member while yet maintaining the spring under compression, said operating member and holder being relatively adjustable at the will of the operator to prevent the release of the carrier from the force of the spring in operating on a shoe.

21. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, means including a spring for con-

trolling said carrier to apply and relieve the pressure, said means being constructed to release the carrier from the force of the spring at a predetermined time in the operation of the machine on the shoe while maintaining the spring under a predetermined degree of stress, and means for lifting the carrier when it is thus released from the force of the spring.

22. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, cam-controlled mechanism including a spring for controlling said carrier to apply and relieve the pressure, said mechanism being constructed to release the carrier from the force of the spring at that time in the cycle of operations of the machine when the tool is traversing the ball-line of the shoe while yet maintaining the spring under stress, and means for lifting the carrier when it is thus released from the force of the spring.

23. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, yieldable means tending constantly to move said carrier in a direction to lift the tool from the shoe, and automatic means including a spring for controlling said carrier to apply and relieve the pressure of the tool on the shoe at different respective times in the operation of the machine, said last-named means being constructed to release the carrier from the force of the spring at a predetermined time in the cycle of operations to permit the tool to be lifted by said yieldable means while yet maintaining the spring under a predetermined degree of stress.

24. In a machine of the class described, a shoe support and a leveling tool relatively movable to cause the tool to operate along the bottom of a shoe, a carrier supporting said tool and movable heightwise of the shoe to press the tool upon the shoe and to relieve the pressure, a spring plunger tending constantly to lift the carrier and the tool, and automatic mechanism including a spring arranged to operate on the carrier against the resistance of said plunger to press the tool on the shoe, said mechanism being constructed to release the carrier from the force of the spring while still maintaining the spring under stress at that time in the cycle of operations when the tool is traversing the ball-line of the shoe to permit the tool to be lifted by the plunger.

25. In a machine of the class described, a shoe support and a leveling tool relatively movable to cause the tool to operate along the bottom of a shoe, means for thus rela-

tively moving the shoe support and the tool in a predetermined cycle of operations of the machine, and automatic means for relieving the pressure of the tool on the shoe at a 5 predetermined time in the cycle of operations, said last-named means being adjustable to vary the time when the pressure is thus relieved.

26. In a machine of the class described, 10 a shoe support and a leveling tool relatively movable to cause the tool to operate along the bottom of a shoe, means for thus relatively moving the shoe support and the tool in a predetermined cycle of operations of the 15 machine, and automatic means comprising a cam for relieving the pressure of the tool on the shoe at a predetermined time in the cycle of operations, said cam being adjustable to vary the time when the pressure is 20 thus relieved.

27. In a machine of the class described, a shoe support and a leveling tool relatively movable to cause the tool to operate along the bottom of a shoe, means for thus relatively moving the shoe support and the tool in a predetermined cycle of operations of the machine, automatic means for pressing the tool on the shoe, and additional means for relieving the pressure at a predetermined time 25 in the cycle of operations, said additional means being adjustable to vary the time when the pressure is thus relieved.

28. In a machine of the class described, a shoe support and a leveling tool relatively 30 movable to cause the tool to operate along the bottom of a shoe, means for thus relatively moving the shoe support and the tool in a predetermined cycle of operations of the machine, automatic means including a cam 35 for pressing the tool on the shoe, and another cam automatically operative independently of said first cam to relieve the pressure at a predetermined time in the cycle of operations, said other cam being adjustable to vary the 40 time when the pressure is thus relieved.

29. In a machine of the class described, a shoe support and a leveling tool relatively 45 movable to cause the tool to operate along the bottom of a shoe, means for thus relatively moving the shoe support and the tool in a predetermined cycle of operations of the machine, and automatic means for pressing the tool on the shoe and for relieving the pressure at different respective times in the cycle 50 of operations of the machine, said automatic means being adjustable to vary the time when the pressure is relieved independently of the time when it is applied.

30. In a machine of the class described, a shoe support and a leveling tool relatively 55 movable to cause the tool to operate along the bottom of a shoe, means for thus relatively moving the shoe support and the tool in a predetermined cycle of operations of the machine, and automatic means for pressing the 60

tool on the shoe, for relieving the pressure, and for thereafter again applying the pressure in the cycle of operations of the machine, said automatic means being adjustable to vary the duration of the pressure relief. 70

31. In a machine of the class described, a shoe support and a leveling tool relatively movable to cause the tool to operate along the bottom of a shoe, means for thus relatively moving the shoe support and the tool in a 75 predetermined cycle of operations of the machine, a spring for pressing said tool yielding on the shoe, and automatic means for increasing and relaxing the force of said spring at different respective times in the 80 cycle of operations of the machine, said last-named means being adjustable to vary the time when the force of the spring is thus relaxed.

32. In a machine of the class described, a 85 shoe support and a leveling tool relatively movable to cause the tool to operate along the bottom of a shoe, means for thus relatively moving the shoe support and the tool in a predetermined cycle of operations of the machine, a spring for pressing said tool yielding on the shoe, a cam for increasing the stress of said spring at a predetermined time 90 in the cycle of operations of the machine, and means operative independently of said cam to 95 relieve the stress of the spring at another time in the cycle.

33. In a machine of the class described, a 100 shoe support and a leveling tool relatively movable to cause the tool to operate along the bottom of a shoe, means for thus relatively moving the shoe support and the tool in a predetermined cycle of operations of the machine, a spring for pressing said tool yielding on the shoe, a cam for increasing the stress of said spring at a predetermined time 105 in the cycle of operations of the machine, and means operative independently of said cam to relieve the stress of the spring at another time in the cycle, said last-named means being adjustable to vary the time when the stress of 110 the spring is thus relieved.

34. In a machine of the class described, a shoe support and a leveling tool relatively 115 movable to cause the tool to operate along the bottom of a shoe, means for thus relatively moving the shoe support and the tool in a predetermined cycle of operations of the machine, a spring for pressing said tool yielding on the shoe, a cam for increasing the stress of said spring at a predetermined time 120 in the cycle of operations of the machine, and mechanism including a cam automatically operative independently of said first cam to relieve the stress of the spring at a variably predetermined time in the cycle of operations. 125

35. In a machine of the class described, a shoe support and a leveling tool relatively 130 movable to cause the tool to operate along the bottom of a shoe, means for thus rela-

tively moving the shoe support and the tool in a predetermined cycle of operations of the machine, automatic means comprising a cam and a member engaged and moved by said cam to press the tool on the shoe, and additional automatic means for holding said member in the position to which it is moved by the cam and for releasing it independently of the cam at a predetermined time in the 10 cycle of operations.

36. In a machine of the class described, a shoe support and a leveling tool relatively movable to cause the tool to operate along the bottom of a shoe, means for thus relatively 15 moving the shoe support and the tool in a predetermined cycle of operations of the machine, automatic means comprising a cam and a member engaged and moved by said cam to press the tool on the shoe, a controlling device for holding said member in the position to which it is moved by the cam, and an adjustable cam for operating the controlling device to release said member and thereby to relieve the pressure of the tool on the 20 shoe at a variably predetermined time in the cycle of operations of the machine.

37. In a machine of the class described, a shoe support and a leveling tool relatively movable to cause the tool to operate along 30 the bottom of a shoe, means for thus relatively moving the shoe support and the tool in a predetermined cycle of operations of the machine to cause the tool to traverse the ball-line of the shoe at different successive times in 35 the cycle, and automatic means for relieving the pressure of the tool on the shoe each time that the tool traverses the ball-line, said last-named means being adjustable to vary the time in the cycle of operations at which each 40 relief of the pressure takes place.

38. In a machine of the class described, a shoe support and a leveling tool relatively movable to cause the tool to operate along the bottom of a shoe, means for thus relatively 45 moving the shoe support and the tool in a predetermined cycle of operations of the machine to cause the tool to traverse the ball-line of the shoe at different successive times in the cycle, and automatic means comprising a plurality of cams for relieving the pressure of the tool on the shoe each time that the tool traverses the ball-line, each of said cams being adjustable independently of the others to vary the time in the cycle of operations at 55 which the relief of pressure controlled thereby takes place.

39. In a machine of the class described, a shoe support and a leveling tool relatively

movable to cause the tool to operate along the bottom of a shoe, means for thus relatively 60 moving the shoe support and the tool in a predetermined cycle of operations of the machine, a plurality of cams for pressing the tool on the shoe at different times in the cycle 65 of operations, and mechanism operative independently of said cams to relieve the pressure of the tool on the shoe in predetermined time relation to the different applications of the pressure.

40. In a machine of the class described, a shoe support and a leveling tool relatively movable to cause the tool to operate along the bottom of a shoe, means for thus relatively 70 moving the shoe support and the tool in a predetermined cycle of operations of the machine, a plurality of cams for pressing the tool on the shoe at different times in the cycle 75 of operations, and mechanism operative independently of said cams to relieve the pressure of the tool on the shoe in predetermined 80 time relation to the different applications of the pressure, said mechanism being adjustable to vary the times in the cycle at which different reliefs of the pressure take place.

41. In a machine of the class described, a shoe support and a leveling tool relatively movable to cause the tool to operate along the bottom of a shoe, means for thus relatively 85 moving the shoe support and the tool in a predetermined cycle of operations of the machine, a plurality of cams for pressing the tool on the shoe at different times in the cycle 90 of operations, and automatic mechanism including a device common to the several cams for controlling independently of said cams 95 the relief of pressure of the tool on the shoe after the pressure has been applied by the action of each cam.

42. In a machine of the class described, a shoe support and a leveling tool relatively 100 movable to cause the tool to operate along the bottom of a shoe, means for thus relatively moving the shoe support and the tool in a predetermined cycle of operations of the machine, a plurality of cams for pressing the tool on the shoe at different times in the cycle 105 of operations, a member common to the several cams for controlling the relief of the pressure of the tool on the shoe after the pressure has been applied by each cam, and auxiliary cam mechanism for controlling said member to determine the times in the cycle 110 when the relief of the pressure takes place.

In testimony whereof I have signed my name to this specification.

ERASTUS E. WINKLEY.
